UNITED STATES PATENT OFFICE.

BERT RIVKIN, OF NEW YORK, N. Y.

STREET OR STATION INDICATOR FOR TRAMWAYS.

SPECIFICATION forming part of Letters Patent No. 760,759, dated May 24, 1904.

Application filed June 24, 1903. Serial No. 162,893. (No model.)

To all whom it may concern:

Be it known that I, BERT RIVKIN, a citizen of the United States, residing at New York, in the county of New York and State of New York, have invented certain new and useful Improvements in Street and Station Indicators for Tramway or other Cars, of which the following is a specification, such as will enable those skilled in the art to which it appertains to make and use the same.

The object of this invention is to provide an improved street and station indicator for tramway and other cars which is designed to be placed in a car and by means of which the names of the various streets on the line of a tramway or street-car track or the stations on a railway may be displayed in such a manner as to be conveniently read by the occupants of a car; and with this and other objects in view the invention consists in an indicator of the class described constructed as hereinafter described and claimed.

The invention is fully disclosed in the following specification, of which the accompanying drawings form a part, in which the separate parts of my improvement are designated by suitable reference characters in each of the views, and in which—

Figure 1 is a side view of my improved indicator; Fig. 2, a similar view with one side of the casing removed and part of the construction shown in section; Fig. 3, a sectional plan view, and Fig. 4 a vertical section on the line 4-4 of Fig. 1 and on an enlarged scale.

In the practice of my invention I provide an oblong box or case *a*, the sides *a*² of which are provided in their inner surfaces with a groove *a*³, the ends of which are segmental in form, and the ends of the box or case *a* are also segmental in form, and the grooves *a*³ form tracks or ways, as hereinafter described.

Mounted in the box or case *a* and connected with the side walls *a*² thereof by means of transverse members *b*, which are rigidly secured thereto by screws or other devices *b*², is a rigid frame comprising a central member *b*³, with which the members *b* are rigidly connected or in connection with which said members are integrally formed, and connected with the transverse member *b*, which forms a

part of the said frame, and at each side of the box or case is an endless track or way *b*⁴, and these tracks or ways *b*⁴ are of the same general form as the grooves *a*³ and correspond therewith. The tracks or ways *b*⁴ form a part of the central frame, and the part *b*³ of said frame is provided with end extensions *b*⁵, in which are mounted sprocket-wheels *c* and *c*², and the sprocket-wheel *c* is mounted on a shaft *c*³, which passes through one side of the box or case and is provided with a gear-wheel *c*⁴.

Mounted on the sprocket-wheels *c* and *c*² is an endless chain *d*, the links *d*² of which are provided with rigid side arms *d*³, with which are rigidly connected card-frames *e*, arranged at right angles to the endless chain *d*, and the frames *e* are provided with members *e*², which engage the endless tracks or ways *b*⁴ and are provided with grooves *e*³ for this purpose. Each of the frames *e* consists of end members *e*⁴ and an outer transverse member *e*⁵, provided, respectively, with slots or openings *e*⁶ and *e*⁷, and passing transversely through the slots *e*⁶ in the end members *e*⁴ of the frames *e* is a rod *f*, the ends of which rest in the grooves *g*³ in the sides *a*² of the main box or case *a*, and each of these rods is provided with a card *f*², and the bottom portion of the sides *a*² of the box or case *a* are provided centrally with vertically-arranged openings *a*⁴, in which the ends of the rods *f* are free to move, and the bottom portion of said box or case is provided with a similar transverse opening *a*⁵, through which the cards *f*² are free to pass.

Passing transversely through the box or case *a* and through the rigid frame member *b*³ is a shaft *g*, one end of which is provided with a gear-wheel *g*², which operates in connection with the wheel *c*⁴, and the other end of which is provided with two ratchet-wheels *g*³ and *g*⁴, the teeth of which project in opposite directions, and beneath the wheels *g*³ and *g*⁴ a lever *h* is pivoted to the side of the box or case *a*, as shown at *i*², and this lever is provided at its upper end with a transverse head *h*³, in which are pivoted two spring-operated dogs *h*⁴ and *h*⁵, which operate, respectively, in connection with the ratchet-wheels *g*³ and *g*⁴, and connected with the lower or free end of the lever *h* and secured to the box or case *a*.

at the opposite sides thereof are springs h^6 and h^7 , which serve to hold said lever normally in a vertical position, as shown in Fig. 1.

Mounted above the box or case a transversely thereof and supported thereon is a shaft i , the opposite ends of which are provided each with a pulley-wheel i^2 , with each of which is connected a cord i^3 , and these cords i^3 are connected with vertically-movable hangers j , which pass through keepers j^2 , connected with the opposite sides of the box or case a . The lower end of each of the vertically-movable hangers j^4 is provided with an inwardly-directed hook member, which members pass into the vertically-arranged slots or openings a^4 in the sides of the box or case a , and the ends f of the rods a^4 are adapted to rest on the hook members j^3 of the vertically-movable hangers j and to be raised thereby.

One or both of the hangers j are provided with a collar k , between which and the upper keeper or keepers j^2 is placed a spiral spring k^2 , and one of the cords i^3 passes loosely over the corresponding wheel i^2 and downwardly between two guide-pulleys k^3 , secured to the bottom portion of one side of the box or case a , and said cord i^3 is connected with an operating-cord m , which passes loosely through the lower end of the lever h , as shown at m^2 , and is supported by two pulleys m^3 , secured to the bottom of the box or case a at or near the opposite ends thereof, and the cord m extends to both ends of the car in which said box or case is placed and may be operated from either end of said car. The cord m is also provided on the opposite sides of the lever h and at a predetermined distance therefrom with stops n and n^2 , and the cord i^3 , which passes between the guide-pulleys k^3 , is provided with a spring member n^3 , which is placed therein between the guide-pulleys k^3 and the pulley i^2 , over which said cord passes.

If my improved indicator is used on a street-car track or tramway, the cards f^2 will bear the names of the various cross-streets along the line of said track or tramway arranged in regular order, and at each pull of the cord m in the direction of the arrow x (shown in Figs. 1 and 3) the chain d will be moved through one space in the direction of the arrows x^2 , (shown in Fig. 2,) and at each pull of the cord m in the direction of the arrow y in Figs. 1 and 3 the chain d will be moved one step in the direction of the arrows y^2 in Fig. 2.

In Figs. 1, 2, and 4 of the drawings one of the rods f , with its card f^2 , is in its lowermost position, and the name on the card f^2 may be read by anybody in the car. At the beginning of the pull on the cord m in the direction of the arrow x the said rod f and its corresponding card f^2 are raised into their normal position within the box or case a by means of the hangers j , and this occurs before the stop n strikes the lower end of the lever h , at which

time the ends of the said rod f are in position to enter the grooves a^3 , and as the pull on the cord m in the direction of the arrow x is continued the dog h^5 engages the ratchet-wheel g^4 and moves it, thereby turning the shaft g and the gear-wheel g^2 , and by this operation the shaft c^3 is turned through one step and the said rod f moves forward one step. At this time the cord m is released, and the hangers j drop into the position shown in Fig. 4, and another rod f drops into the position shown in Figs. 1, 2, and 4, and another card f^2 is exposed. It will be understood that this operation is repeated as the car proceeds on its way, and when the car reaches the end of the line and starts on the return trip the cord m must be operated from the opposite end of the car, and pulls thereon in the direction of the arrows y in Figs. 1 and 3 will bring the stop n^2 on said cord into operation, and the result will be the same as hereinbefore described except that the movement of the shaft c^3 and of the chain d is reversed, and the operation of my improved indicator would be the same on an ordinary railway except that the names of the stations would take the place on the cards f^2 of the names of cross-streets.

My improved indicator is exceedingly simple in construction and operation and perfectly adapted to accomplish the result for which it is intended and may be employed on street-cars or on ordinary railways and whenever devices of this kind are required.

My invention is not limited to the exact form, construction, and arrangement of the various parts thereof as herein shown and described, as many changes therein and modifications thereof may be made without departing from the spirit of my invention or sacrificing its advantages, and I reserve the right to make all such alterations therein as fairly come within the scope of the invention.

Having fully described my invention, what I claim as new, and desire to secure by Letters Patent, is—

1. In a device of the class described, a box or case, the side members of which are provided with interior grooves forming tracks or ways, a rigid frame secured in the box or case and provided with tracks or ways which correspond with said grooves, an endless chain mounted on said frame, card-frames connected with the links of said chain and movable therewith and adapted to engage the tracks or ways connected with said frame, card-supports mounted in said card-frames and the ends of which are adapted to travel in said grooves, devices for moving said chain step by step and means whereby at each movement of the chain a card is exposed through the box or case, substantially as shown and described.

2. A device of the class described, provided with an endless chain mounted on sprocket-

wheels, cards slidably attached to said chain, devices for moving said chain step by step and comprising two ratchet-wheels secured to one end of the shaft of one of said sprocket-
5 wheels, a lever pivotally supported adjacent to said ratchet-wheels and provided with two spring pawls or dogs, one of which operates in connection with one of said ratchet-wheels and the other in connection with the other
10 of said ratchet-wheels, substantially as shown and described.

3. An indicator of the class described, comprising an oblong box or case, an endless chain movable therein, card-frames connected with the links of said chain, cards slidably mounted in said frames, means for moving said chain step by step, means whereby at each movement of said chain a card will be displayed through said box or case, and devices connected with the means for moving the chain step by step for withdrawing the card into the box or case and into its frame, substantially as shown and described.

4. In the device of the class described, an ob-
25 long box or case, provided with a transverse slot in the bottom and corresponding vertically-arranged slots in the sides thereof, a rigid frame supported in said box or case and provided at its opposite ends with sprocket-
30 wheels, an endless member mounted on said

wheels, card-frames connected with said endless member and movable therewith, card-supports mounted in said frames, devices for moving said member step by step, and means whereby at each movement of said member a 35 card is dropped through the slots in the box or case, and devices for withdrawing said card into the box or case and into its frame, substantially as shown and described.

5. A device of the class described, comprising an oblong box or case, an endless member mounted therein and movable step by step, card-frames movably connected with said endless member and movable therewith, card-supports mounted in said frames and mov- 45 able therein, means whereby at each movement of said endless member a card is exposed through the box or case, and devices for returning the card into the box or case and into its frame at the beginning of the next move- 50 ment of the endless member, substantially as shown and described.

In testimony that I claim the foregoing as my invention I have signed my name, in presence of the subscribing witnesses, this 16th 55 day of June, 1903.

BERT RIVKIN.
